UNITED STATES PATENT OFFICE.

JOSEPH HOFFMAN, OF NEW YORK, N. Y., ASSIGNOR TO HENRY BEROLZ-HEIMER, OF SAME PLACE.

PENCIL-SHARPENER.

SPECIFICATION forming part of Letters Patent No. 291,597, dated January 8, 1884.

Application filed October 26, 1883. (No model.)

To all whom it may concern:

Be it known that I, JOSEPH HOFFMAN, of the city and county of New York, and State of New York, have invented certain new and useful Improvements in Pencil-Sharpeners, of which the following is a specification.

My invention has to do with pencil-sharpening machines which contain in combination cutting or sharpening devices proper and means for feeding the pencil to said devices.

My invention relates more particularly to the means for feeding the pencil; and it mainly consists in a feed organization which automatically carries forward the pencil in proportion as it is cut and sharpened. Under my invention the feed mechanism is spring-controlled, and has imparted to it a tendency to advance the pencil held in its grasp toward the cutting and sharpening devices, this movement of the pencil taking place automatically and in proportion to the extent to which its end is reduced or cut away. The feed mechanism which I prefer to employ consists of two rolls, which can yield to permit the passage of a pencil between them, combined with a driving-spring, which, when the pencil is inserted between the rolls, will act to rotate the latter in a direction to feed forward the pencil to the cutter.

My improvement has been designed with special reference to the needs of the pencil-sharpener described in Letters Patent No. 230,338, of July 20, 1880, and it is in this connection that I have illustrated it in the accompanying drawings. I desire it to be understood, however, that it can be applied to pencil-sharpeners generally.

In the drawings, Figure 1 is a longitudinal central section of a pencil-sharpener made in accordance with my invention. Fig. 2 is a side elevation of the upper portion of the machine. Fig. 3 is a front elevation, partly in section, of the upper portion of the machine. Fig. 4 is a side elevation with the driving-spring in section on line 4 4 of Fig. 3.

A is the base of the machine.

B is the stand or case in which the working parts are contained.

C is a drawer to catch the shavings.

D is the rotary shaft, having crank-handle 50 E, and carrying the cutter F and the revolving file L, which latter is rotated in an opposite direction to the shaft D through the instrumentality of its pinion K, which engages a fixed internal gear, K', in the case B. 55

The parts thus far described are substantially the same in construction and operation as those described in Letters Patent No. 230,338, above referred to, and require no further description here. 60

I now come to that portion of the machine in which my improvement is contained.

In the front of the case B are mounted the two feed-rolls G G', so as to freely revolve. They are made of any suitable material—usually vulcanized rubber; or they may be simply coated with rubber or other material which will not injure or mark the pencil. The rolls are grooved at a to afford a channel into which the pencil can be inserted. They are capable 70 of moving apart to allow the pencil to be entered between them, for which purpose the journals of the lower roll are in vertical slots b in the case, and they are held together, so as to exert clamping pressure on the pencil, by 75 means of springs c. The axle or journal of one of the rolls—in this instance the lower roll, G—is prolonged at one end, and on this end is put the crank-handle H. Surrounding that portion of the axle which projects beyond the 80 case is a volute spring, I, having its inner end connected to the axle and its outer end fastened to the case B. By turning the handle H in the direction of the arrow, Fig. 2, the spring I can be wound up. If then the handle be released, the spring will unwind, and in so doing will revolve the lower roll with considerable force. With a view to prevent damage that might result by turning the handle H in the wrong direction, the spring is so connected with the axle that the two will engage only when the handle is turned in the proper direction, to which end a beveled catch or stud, c', is formed on the axle, and a slot or hole, d, is made in the inner extremity of the 95 spring, the arrangement being such that when the handle is turned by hand in the direction of the arrow the square shoulder of the pro-

jection will catch in the slot, and thus wind up the spring; but when, on the other hand, the handle is turned in the wrong direction, the beveled face of the projection will meet the slot, and consequently the end of the spring will ride over without engaging the projection.

The operation is as follows: The spring is first wound up by turning the handle in the direction of the arrow, and, while the handle is still held, the pencil *x* is forced into the bite of the rolls, as indicated in Fig. 1. The handle being then released, the spring asserts itself, and, by rotating the rolls, carries forward the pencil into the sharpener or cutter. The crank *E* is then rapidly turned, with the effect of cutting and sharpening the end of the pencil, the latter being automatically fed forward in proportion as it is cut away, until it is properly sharpened. When this has been done, the pencil is withdrawn by turning the crank *H* again in the direction of the arrow, thus causing the rolls to rotate against the stress of the spring. After the pencil is withdrawn—unless another one is to be introduced—the spring is allowed to unwind by permitting the handle *H* to revolve slowly. If at any time the feed-spring should fail to feed fast enough, its action can be assisted by gently turning the crank *H* in the proper direction to advance the pencil.

Having described my improvements and the preferred embodiment of the same, what I claim as new and of my own invention is—

1. In a pencil-sharpener, the combination, with the cutter, of automatic spring-controlled pencil-feed mechanism, substantially as hereinbefore set forth. 35

2. The combination of the pencil sharpening or cutting mechanism proper, the feed-rolls, and the spring, arranged and operating to rotate the same in the direction requisite to advance the pencil held between them toward the cutting mechanism, substantially as hereinbefore set forth. 40

3. The combination of pencil-sharpening mechanism, pencil-feed rolls, held together with yielding pressure, and the roll-propelling spring, as and for the purposes hereinbefore set forth. 45

4. The combination of the pencil-sharpening mechanism, the feed-rolls, the crank or handle *H*, and the spring *I*, under the arrangement and for operation substantially as hereinbefore set forth. 50

In testimony whereof I have hereunto set my hand this 24th day of October, 1883.

JOSEPH HOFFMAN.
